UPHOLSTERED SEAT

Evalin S. Gilbert, 2121 N. Bay Shore Drive,
Miami, Fla. 33137

Filed June 6, 1972, Ser. No. 260,350

Term of patent 14 years

Int. Cl. D6—02

U.S. Cl. D6—62

FIG.1

FIG.2

FIG. 1 is a perspective view showing the front and end of an upholstered seat incorporating my new design; and

FIG. 2 is a perspective view showing the same end and the rear view of the upholstered seat of FIG. 1.

The end of the seat not shown is a mirror image of the end shown.

I claim:

The ornamental design for an upholstered seat, substantially as shown and described.
